(57) **CLAIM**

The ornamental design for a lamp, as shown and described.

DESCRIPTION

FIG. 1.1 is a front perspective view of a lamp showing my new design;

FIG. 1.2 is a top view thereof;

FIG. 1.3 is a right side view thereof;

FIG. 1.4 is a left side view thereof;

FIG. 1.5 is a rear view thereof;

FIG. 1.6 is a front view thereof; and,

FIG. 1.7 is a bottom view thereof.

The broken lines shown in the figures illustrate portions of the rear part of the lamp that form no part of the claimed design.
